(57) **ABSTRACT**

Disclosed herein is an antenna device that includes an antenna coil having a planar coil pattern, a magnetic sheet that covers one main surface of the antenna coil, and a resin layer provided on the other main surface of the antenna coil and along the coil pattern. The resin layer is substantially the same planar shape as the planar coil pattern.

ANTENNA DEVICE AND MANUFACTURING
METHOD THEREOF

BACKGROUND OF THE INVENTION

Field of the Invention

The present invention relates to an antenna device and a manufacturing method thereof and, more particularly to an antenna device suitable for NFC (Near Field Communication) system and a manufacturing method thereof.

Description of Related Art

In recent years, a mobile electronic apparatus such as a smartphone is provided with an RFID (Radio Frequency Identification, i.e., individual identification by radio waves) system and further provided with, as a communication means of the RFID, an antenna device for performing near field communication with a reader/writer. For example, a conventional antenna device described in Japanese Patent Application Laid-Open No. 2008-117944 has a base substrate made of a plastic film, an antenna coil formed on the base substrate, a metallic shield plate provided at a position overlapping the antenna coil in a planar view, and a magnetic core member provided between the antenna coil and metallic shield plate. Such an antenna device is accommodated in a casing of a mobile electronic apparatus such as a smartphone and is disposed on a surface of a battery pack or a surface of a printed circuit board.

However, recently, a reduction in thickness of the mobile electronic apparatus is highly required, and a further thickness reduction is required for the antenna device itself. Further, in a case where the antenna device is mounted on a surface of a heating element such as a battery pack, the base substrate may block heat radiation from the battery pack because the antenna coil is supported on the base substrate. Further, because the base substrate is made of a dielectric material, an inter-line capacitance of the antenna coil becomes large due to an intervention of the dielectric material between lines of the antenna coil, making it difficult to achieve frequency matching.

SUMMARY

It is therefore an object of the present invention to provide an antenna device having a very small thickness and having excellent heat radiation characteristics and excellent antenna characteristics, and a manufacturing method thereof.

To solve the above problems, an antenna device according to the present invention includes an antenna coil having a planar coil pattern, a magnetic sheet that covers one main surface of the antenna coil, and a resin layer provided on the other main surface of the antenna coil and along the coil pattern.

According to the present invention, the antenna coil is supported by the magnetic sheet, and a resin support film is not provided, whereby a reduction in thickness of the antenna device can be achieved. Further, the antenna coil is covered by the resin layer and, thus, the surface of the antenna coil can be protected thereby. Further, because the support film is not provided, heat radiation from the heating body is not blocked by the support film even when the antenna device is provided on the surface of the heating body. Further, the support film having a high dielectric constant is removed and absent, so that it is possible to solve the problem that it is difficult to achieve frequency matching of the antenna coil due to a large line capacitance of the coil by the support film.

2

In the present invention, the antenna coil is preferably bonded to one main surface of the magnetic sheet via an adhesive layer. According to this configuration, the antenna coil that has previously been formed on the support film can be transferred to the surface of the magnetic sheet, thus allowing the antenna coil to be reliably formed on the magnetic sheet.

In the present invention, the magnetic sheet is preferably provided so as to avoid an area overlapping an outer peripheral end and an inner peripheral end of the antenna coil in a planar view. With this configuration, it is possible to easily achieve electrical connection between the antenna coil and a communication circuit such as an NFC chip.

In the present invention, a metallic body is may positioned on the other main surface side of the magnetic sheet. According to this configuration, the magnetic sheet is interposed between the metallic body and the antenna coil, so that it is possible to reduce influence of the metallic body on the antenna coil.

In the present invention, a printed circuit board may be positioned on the other main surface side of the magnetic sheet. According to this configuration, a communication circuit can be constructed on the printed circuit board, facilitating electrical connection between the communication circuit and the antenna coil.

In the present invention, the resin layer preferably contains metal that acts as a catalyst when the antenna coil is formed by plating. According to this configuration, the antenna coil can be formed by plating on the surface of the resin layer. By bonding the formed antenna coil to the surface of the magnetic sheet, the antenna device according to the present invention can be easily manufactured.

The antenna device according to the present invention preferably further includes first and second contact plugs that penetrate the magnetic sheet to be connected respectively to the outer and inner peripheral ends of the antenna coil. According to this configuration, in a case where the communication circuit to be connected to the antenna coil is provided on the one main surface of the antenna coil, electrical connection between the communication circuit and the antenna coil can be reliably achieved by the first and second contact plugs.

In the antenna device according to the present invention, the outer and inner peripheral ends of the antenna coil may be exposed without being covered by the resin layer. According to this configuration, electrical connection between the communication circuit and the antenna coil can be easily and reliably achieved.

A manufacturing method according to the present invention is a method of manufacturing an antenna device including an antenna coil and a magnetic sheet, the method includes the steps of: forming, on a surface of a resin support film, a resin layer having the same planar shape as that of the antenna coil; forming, by plating, the antenna coil on a surface of the resin layer; forming the magnetic sheet on one main surface side of the antenna coil; and removing the support film from the resin layer.

According to the present invention, it is possible to manufacture, with ease and at low cost, an antenna device having a very small thickness and excellent in heat radiation characteristics and excellent antenna characteristics.

In the present invention, it is preferable that the resin layer contains a catalyst for electroless plating and that the step of forming the antenna coil by plating includes a step of forming, by electroless plating, a ground plating layer constituting the antenna coil on the surface of the resin layer and a step of making the ground plating layer grow by electro-

lytic plating. According to this configuration, it is possible to form the antenna coil on the surface of the support film and thereby to manufacture an antenna device having a very small thickness and excellent in antenna characteristics.

In the present invention, the step of forming the antenna coil by plating preferably includes a step of adhering the catalyst for electroless plating to the surface of the resin layer, a step of forming, by electroless plating, a ground plating layer constituting the antenna coil on the surface of the resin layer to which the catalyst has been adhered, and a step of making the ground plating layer grow by electrolytic plating. According to this configuration, it is possible to form the antenna coil on the surface of the support film and thereby to manufacture an antenna device having a very small thickness and excellent in antenna characteristics.

The manufacturing method according to the present invention preferably further includes a step of removing the resin layer that covers outer and inner peripheral ends of the antenna coil after removal of the support film. According to this configuration, electrical connection between the antenna coil and a communication circuit can be easily achieved.

As explained above, according to the present invention, it is possible to provide an antenna device having a very small thickness and having excellent heat radiation characteristics and excellent antenna characteristics and a manufacturing method thereof.

BRIEF DESCRIPTION OF THE DRAWINGS

The above features and advantages of the present invention will be more apparent from the following description of certain preferred embodiments taken in conjunction with the accompanying drawings, in which:

FIG. 1 is an exploded perspective view illustrating a configuration of an antenna device according to a first embodiment of the present invention;

FIGS. 2A to 2C are planar views separately illustrating individual layers constituting the antenna device according to the first embodiment in which FIG. 2A illustrates a magnetic sheet, FIG. 2B illustrates an antenna coil, and FIG. 2C illustrates a resin layer;

FIGS. 3A and 3B are cross-sectional views of the antenna device according to the first embodiment in which FIG. 3A is a cross-sectional view taken along a line A-A' of FIGS. 2A to 2C, and FIG. 3B is a cross-sectional view taken along a B-B' line of FIGS. 2A to 2C;

FIGS. 4A to 4E are exemplary views for explaining an example of a manufacturing method for the antenna device shown in FIG. 1;

FIGS. 5A to 5F are exemplary views for explaining another example of a manufacturing method for the antenna device shown in FIG. 1;

FIGS. 6A to 6C are cross-sectional views illustrating an implementation example of the antenna device shown in FIG. 1 in which FIG. 6A illustrates a case where the antenna device is brought into contact with a battery pack, and FIGS. 6B and 6C illustrate a case where the antenna device is brought into contact with a printed circuit board;

FIG. 7 is a cross-sectional view illustrating a configuration of an antenna device according to a second embodiment of the present invention; and

FIG. 8 is an exemplary view for explaining a manufacturing method for the antenna device according to the second embodiment.

DETAILED DESCRIPTION OF THE EMBODIMENTS

FIG. 1 is an exploded perspective view illustrating a configuration of an antenna device according to the first

embodiment of the present invention. FIGS. 2A to 2C are planar views separately illustrating individual layers constituting the antenna device according to the first embodiment. FIG. 2A illustrates a magnetic sheet, FIG. 2B illustrates an antenna coil, and FIG. 2C illustrates a resin layer. FIGS. 3A and 3B are cross-sectional views of the antenna device according to the first embodiment. FIG. 3A is a cross-sectional view taken along a line A-A' of FIGS. 2A to 2C, and FIG. 3B is a cross-sectional view taken along a B-B' line of FIGS. 2A to 2C.

As illustrated in FIG. 1, FIGS. 2A to 2C, and FIGS. 3A and 3B, an antenna device 1 according to the present embodiment includes an antenna coil 10 constituted of a planar coil pattern, a magnetic sheet 11 provided on one main surface 10a of the antenna coil 10, and a resin layer 12 provided on the other main surface 10b of the antenna coil 10. An adhesive layer 13 is formed on one main surface 11a of the magnetic sheet 11 so that the antenna coil 10 is provided on the main surface 11a of the magnetic sheet 11 through the adhesive layer 13.

The antenna coil 10 is constituted of a substantially rectangular spiral pattern and is formed while depicting a loop as large as possible along the magnetic sheet 11 so as to make a size of an opening inside the spiral large. The antenna coil 10 is preferably made of Cu (copper) having high conductivity and advantageous in terms of workability and cost. A thickness of the antenna coil 10 is preferably in a range of 30 μm to 50 μm . Although details will be described later, an outer peripheral end 10c and an inner peripheral end 10d of the antenna coil 10 are connected to a communication circuit such as an NFC chip.

The magnetic sheet 11 provides a magnetic path of a magnetic flux that the antenna coil 10 generates and can be made from magnetic metal powder containing resin obtained by dispersing magnetic metal powder in a resin binder. As the magnetic metal powder, Permalloy (Fe—Ni alloy), Super Permalloy (Fe—Ni—Mo alloy), Sendust (Fe—Si—Al alloy), Fe—Si alloy, Fe—Co alloy, Fe—Cr alloy, Fe—Cr—Si alloy or the like can be used. As the resin binder, phenol resin, urea resin, melamine resin, polytetrafluoroethylene, polyethylene, polypropylene, polystyrene, polyether sulfone, polyphenylene sulfide, PET (polyethylene terephthalate), PET (polybutylene terephthalate), polyarylate, silicone resin, dialyl phthalate, polyimide, or the like can be used.

For a reduction in thickness of the antenna device 1, a thickness of the magnetic sheet 11 is preferably as thin as possible within a range where function of the magnetic sheet 11 can be fulfilled. Specifically, the thickness of the magnetic sheet 11 is preferably in a range from 30 μm to 80 μm . The magnetic sheet 11 has contact holes 11c and 11d to expose therethrough the outer peripheral end 10c and the inner peripheral end 10d of the antenna coil 10. The outer peripheral end 10c and the inner peripheral end 10d of the antenna coil 10 are connected to contact plugs (not illustrated) embedded in the contact holes 11c and 11d, respectively and are electrically connected to a communication circuit (not illustrated) through the contact plugs penetrating the magnetic sheet 11.

The resin layer 12 may mechanically protect a surface of the antenna coil 10 and serves as a base film of the antenna coil 10 upon formation thereof. The resin layer 12 is made of, e.g., epoxy resin and preferably has a thickness of 1 μm to 5 μm . A planar shape of the resin layer 12 need not completely coincide with a planar shape of the antenna coil 10. For example, a part (particularly, outer peripheral end 10c and inner peripheral end 10d) of the surface of the

antenna coil **10** may be exposed through a removed portion of the resin layer **12**. Thus, it is only necessary for the resin layer **12** to be formed in a formation area of the antenna coil **10** in a planar view.

The resin layer **12** may contain a metal such as palladium that acts as a catalyst when the antenna coil **10** is formed by plating. In the case where the resin layer **12** does not contain such a metal and thus has insulating properties, the resin layer can serve as an insulating film that electrically protects the antenna coil **10**.

FIGS. 4A to 4E are exemplary views for explaining an example of a manufacturing method for the antenna device **1**.

First, as illustrated in FIG. 4A, a resin support film **16** is prepared, and the resin layer **12** having the same planar shape as that of the antenna coil **10** is formed on a surface of the support film **16**. As the support film **16**, a PET film having a thickness of 30 μm to 50 μm is preferably used. The resin layer **12** contains a catalyst, such as palladium, for electroless plating. The resin layer **12** can be formed by screen-printing an epoxy resin paste containing palladium followed by curing. In order to facilitate a removal process (to be described later) of the support film **16**, coating may be previously applied to the surface of the support film **16** before formation of the resin layer **12**.

Then, as illustrated in FIG. 4B, electroless copper plating is applied to the support film **16** on which the resin layer **12** containing the catalyst has been formed to thereby form a base plating layer **10e** of the antenna coil **10** on an upper surface of the resin layer **12**. Further, as illustrated in FIG. 4C, the base plating layer **10e** of the antenna coil **10** is made to grow by electrolytic copper plating to thereby complete formation of the antenna coil **10**.

Then, as illustrated in FIG. 4D, the magnetic sheet **11** on the main surface **11a** of which the adhesive layer **13** has been formed is prepared, and the antenna coil **10** is bonded to a surface of the adhesive layer **13**. After that, as illustrated in FIG. 4E, the support film **16** is removed from the antenna coil **10**. Formation of the antenna device **1** is thus completed.

FIGS. 5A to 5F are exemplary views for explaining another example of the manufacturing method for the antenna device **1**.

As illustrated in FIGS. 5A to 5F, this manufacturing method is featured in that the resin layer not containing the catalyst for electroless plating is formed (FIG. 5A), and a catalyst **17** is adhered to the surface of the formed resin layer **12** (FIG. 5B), followed by electroless plating (FIG. 5C). Other processes (FIGS. 5D to 5F) are the same as those illustrated in FIGS. 4C to 4E, so redundant description thereof will be omitted. Using a material to which the catalyst is easily adhered as a material of the resin layer **12** allows the catalyst that is coated or dispersed to the entire surface of the support film **16** to be adhered only to the surface of the resin layer **12**. After that, by performing electroless plating and electrolytic plating, the antenna coil **10** having a desired planar coil pattern can be formed. In the antenna device **1** manufactured by this manufacturing method, the surface of the resin layer **12** exposed after removal of the support film **16** assumes insulating properties. Thus, it is possible to insulate the antenna coil **10** from other circuits or a casing by the resin layer **12**.

In the antenna device **1** according to the present embodiment, although the antenna coil **10** is provided on the magnetic sheet **11**, the resin support film **16** that supports the antenna coil **10** at its formation stage is not provided. A recent mobile electronic apparatus represented by a smartphone is required to be reduced in thickness to the limit and,

in the present embodiment, the support film **16** is removed in the manufacturing process, so that the antenna device **1** can be reduced in thickness and weight by just those of the support film **16**, leading to a reduction in thickness and weight of a mobile electronic apparatus such as a smartphone in which the antenna device is incorporated.

Further, the resin support film **16** is a dielectric body, so that if the support film **16** is brought into contact with the antenna coil **10**, an inter-line capacitance of the antenna coil **10** becomes large. In frequency matching of the antenna device **1**, a desired resonance frequency is set by adding a capacitance to an antenna circuit. However, if an original capacitance is very large due to a large inter-line capacitance, adjustment of a frequency made by addition of the capacitance is difficult. That is, it is difficult to achieve matching at a target frequency (e.g., 13.56 MHz) by adding the capacitance in frequency matching. However, when the support film **16** is not provided, the inter-line capacitance can be reduced, thereby facilitating antenna frequency matching.

FIGS. 6A to 6C are cross-sectional views illustrating an implementation example of the antenna device **1**. FIG. 6A illustrates a case where the antenna device **1** is brought into contact with a battery pack, and FIGS. 6B and 6C illustrate a case where the antenna device **1** is brought into contact with a printed circuit board.

As illustrated in FIG. 6A, the antenna device **1** according to the present embodiment can be fitted to a surface of a battery pack **14**. In this case, the battery pack **14** needs to be disposed on the other main surface **11b** side of the magnetic sheet **11**. In the absence of the magnetic sheet **11**, the antenna coil **10** may not function as a desired antenna under influence of a metallic casing of the battery pack **14**; however, in the present embodiment, the magnetic sheet **11** is provided between the antenna coil **10** and the battery pack **14**, whereby influence of the metallic body can sufficiently be reduced.

The battery pack **14** generates heat with charge and discharge of a battery. However, because the support film **16** is not provided in the antenna device **1**, heat radiation from the battery pack **14** is not blocked by the resin support film **16**. Thus, the antenna device **1** has high heat radiation performance.

Further, as illustrated in FIG. 6B, the antenna device **1** according to the present embodiment can be fitted onto a printed circuit board **15**. As illustrated, the battery pack **14** is provided on the other main surface **11b** side of the magnetic sheet **11**, and the printed circuit board **15** is provided between the battery pack **14** and the antenna device **1**. While the magnetic sheet **11** is provided between the antenna coil **10** and the printed circuit board **15**, the outer peripheral end **10c** and the inner peripheral end **10d** of the antenna coil **10** are respectively connected to contact pins **15a** and **15b** of the printed circuit board **15** via first and second contact plugs **18a** and **18b** embedded in the contact holes **11c** and **11d** of the magnetic sheet **11**, respectively, whereby the antenna coil **10** can be easily connected to the printed circuit board **15**. Alternatively, it is possible to bring the contact pins **15a** and **15b** of the printed circuit board **15** into direct contact with the outer peripheral end **10c** and inner peripheral end **10d** of the antenna coil **10** without using the contact plugs **18a** and **18b**.

Assume that a semiconductor IC chip **15c** is mounted on the printed circuit board **15** and generates heat as illustrated in FIG. 6B. Also in this case, since the resin support film **16** is not provided in the antenna device **1**, heat radiation from

the semiconductor IC chip **15c** is not blocked. Thus, the antenna device **1** has high heat radiation performance.

As illustrated in FIG. 6C, the antenna device **1** according to the present embodiment can be provided such that the antenna coil **10** side thereof faces the printed circuit board **15**. In this case, the contact pins **15a** and **15b** of the printed circuit board **15** penetrate the resin layer **12** to be electrically connected to the outer peripheral end **10c** and the inner peripheral end **10d** of the antenna coil **10**, respectively. Alternatively, it is possible to partially remove the resin layer **12** that covers the outer peripheral end **10c** and the inner peripheral end **10d** of the antenna coil **10** and then to connect the contact pins **15a** and **15b** to exposed surfaces of the outer peripheral end **10c** and the inner peripheral end **10d**, respectively. In the implementation example illustrated in FIG. 6C, the contact holes **11c** and **11d** need not be formed in the magnetic sheet **11**.

As described above, in the antenna device **1** according to the present embodiment, the antenna coil **10** is supported by the magnetic sheet **11**, and the resin support film **16** is removed and absent, whereby a reduction in thickness of the antenna device can be achieved. Further, the support film **16** is removed and absent, so that heat radiation is not blocked by the support film **16** even when the antenna coil **10** is provided on the surface of a heating body such as the battery pack **14**. Further, the support film **16** having a high dielectric constant is removed and absent, so that it is possible to solve the problem that it is difficult to achieve frequency matching due to a large line capacitance of the coil by the support film **16**.

FIG. 7 is a cross-sectional view illustrating a configuration of the antenna device **2** according to the second embodiment of the present invention. FIG. 8 is an exemplary view for explaining a manufacturing method for the antenna device **2** according to the second embodiment.

As illustrated in FIG. 7, an antenna device **2** according to the present embodiment is featured in that the antenna coil **10** and the resin layer **12** are embedded in the magnetic sheet **11** on the main surface **11a** side such that the resin layer **12** is exposed on the main surface **11a**. The adhesive layer **13**, which is used in the first embodiment, is not provided. Other configurations are substantially the same as those of the antenna device **1** according to the first embodiment. Thus, the antenna device **2** according to the present embodiment can provide the same functions and effects as those of the antenna device **1**.

As illustrated in FIG. 8, the resin layer **12** and the antenna coil **10** are formed on the support film **16**, and a magnetic metal powder resin paste **11e** is coated on the entire surface of the support film **16** so as to cover the resin layer **12** and the antenna coil **10**. Thereafter, the magnetic metal powder resin paste **11e** is cured, and the support film **16** is removed, whereby formation of the antenna device **2** is completed. Processes of forming the resin layer **12** and the antenna coil **10** on the support film **16** are as illustrated in FIGS. 4A to 4C or FIGS. 5A to 5C.

It is apparent that the present invention is not limited to the above embodiments, but may be modified and changed without departing from the scope and spirit of the invention.

For example, although the antenna coil **10** is constituted by a spiral pattern with several turns in the above embodiments, the loop pattern may contain no turns. That is, the antenna coil **10** only needs to be a loop-shaped or a spiral-shaped planar coil pattern.

Further, in the above embodiments, the contact holes **11c** and **11d** are formed in the magnetic sheet **11** so that the contact holes **11c** and **11d** are provided in a limited range

where they overlap pads of the respective outer peripheral end **10c** and the inner peripheral end **10d** of the antenna coil **10** in a planar view. Alternatively, however, the pads of the respective outer peripheral end **10c** and the inner peripheral end **10d** may be exposed together through one large contact hole. That is, in a configuration where the contact hole is formed on the magnetic sheet **11**, the contact hole may be formed so as to overlap the outer peripheral end **10c** and the inner peripheral end **10d** in a planar view.

What is claimed is:

1. An antenna device comprising:
an antenna coil having a planar coil pattern;
a magnetic sheet that covers one main surface of the antenna coil; and
a resin layer provided on the other main surface of the antenna coil and along the coil pattern,
wherein the magnetic sheet is configured so as to avoid an area overlapping with an outer peripheral end and an inner peripheral end of the antenna coil in a planar view.
2. The antenna device as claimed in claim 1, wherein the antenna coil is bonded to one main surface of the magnetic sheet via an adhesive layer.
3. The antenna device as claimed in claim 2, wherein a metallic body is positioned on the other main surface side of the magnetic sheet.
4. The antenna device as claimed in claim 2, wherein a printed circuit board is positioned on the other main surface side of the magnetic sheet.

5. The antenna device as claimed in claim 1, wherein the resin layer contains metal that acts as a catalyst when the antenna coil is formed by plating.

6. The antenna device as claimed in claim 1, further comprising first and second contact plugs that penetrate the magnetic sheet to be connected respectively to the outer and inner peripheral ends of the antenna coil.

7. The antenna device as claimed in claim 1, wherein outer and inner peripheral ends of the antenna coil are exposed without being covered by the resin layer.

8. A method of manufacturing an antenna device including an antenna coil and a magnetic sheet, the method comprising:

- forming a resin layer having the same planar shape as that of the antenna coil on a surface of a support film;
- forming the antenna coil on a surface of the resin layer by plating;
- forming the magnetic sheet on one main surface side of the antenna coil; and
- removing the support film from the resin layer.

9. The method of manufacturing the antenna device as claimed in claim 8,

wherein the resin layer contains a catalyst for electroless plating, and

wherein the forming the antenna coil by plating includes:

forming a base plating layer on the surface of the resin layer by electroless plating; and

growing the base plating layer by electrolytic plating.

10. The method of manufacturing the antenna device as claimed in claim 8, wherein the forming the antenna coil by plating includes:

adhering the catalyst for electroless plating to the surface of the resin layer;

forming a base plating layer on the surface of the resin layer to which the catalyst has been adhered by electroless plating; and

growing the base plating layer by electrolytic plating.

11. The method of manufacturing the antenna device as claimed in claim 8, further comprising removing the resin layer that covers outer and inner peripheral ends of the antenna coil after the removing.

12. A device comprising:

- a spiral metal pattern having first and second spiral surfaces opposite to each other;
- a magnetic sheet arranged on the first spiral surface of the spiral metal pattern; and
- a spiral resin pattern having third and fourth spiral surfaces opposite to each other, the third spiral surface of the spiral resin pattern being in contact with the second spiral surface of the spiral metal pattern.

13. The device as claimed in claim 12, wherein the spiral resin pattern is substantially the same planar shape as the spiral metal pattern.

14. The device as claimed in claim 12, wherein the spiral resin pattern includes a metal material.

15. The device as claimed in claim 14, wherein the metal material comprises palladium.

16. The device as claimed in claim 12, wherein the spiral resin pattern is substantially free from a metal material.

17. The device as claimed in claim 12, wherein the magnetic sheet has at least one contact hole that expose an outer peripheral end and an inner peripheral end of the first spiral surface of the spiral metal pattern.

18. The device as claimed in claim 12, wherein the second spiral surface of the spiral metal pattern has an outer peripheral end and an inner peripheral end that expose from the spiral resin pattern.

19. The device as claimed in claim 12, wherein the spiral metal pattern is thicker than the spiral resin pattern.

20. An antenna device comprising:

- an antenna coil having a planar coil pattern;
- a magnetic sheet that covers one main surface of the antenna coil;

5

a resin layer provided on the other main surface of the antenna coil and along the coil pattern;

an adhesive layer configured to bond the antenna coil to one main surface side of the magnetic sheet; and

a metallic body positioned on the other main surface side of the magnetic sheet.

21. An antenna device comprising:

an antenna coil having a planar coil pattern;

a magnetic sheet that covers one main surface of the antenna coil;

a resin layer provided on the other main surface of the antenna coil and along the coil pattern;

an adhesive layer configured to bond the antenna coil to one main surface side of the magnetic sheet; and

a printed circuit board positioned on the other main surface side of the magnetic sheet.

22. An antenna device comprising:

an antenna coil having a planar coil pattern;

a magnetic sheet that covers one main surface of the antenna coil; and

a resin layer provided on the other main surface of the antenna coil and along the coil pattern, the resin layer containing metal that acts as a catalyst when the antenna coil is formed by plating.

23. An antenna device comprising:

an antenna coil having a planar coil pattern;

a magnetic sheet that covers one main surface of the antenna coil; and

a resin layer provided on the other main surface of the antenna coil and along the coil pattern, wherein outer and inner peripheral ends of the antenna coil are exposed without being covered by the resin layer.
